The ornamental design for a sports board for carrying a rider, as shown and described.

DESCRIPTION

FIG. 1 is a top and right-rear perspective view of a sports board for supporting a rider showing my new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a top and right-rear perspective view of another embodiment of my new design of FIGS. 1-6;

FIG. 8 is a left side elevational view thereof;

FIG. 9 is a top plan view thereof;

FIG. 10 is a bottom plan view thereof;

FIG. 11 is a front elevational view thereof; and,

FIG. 12 is a rear elevational view thereof.
